(57) **CLAIM**

The ornamental design for a plastic film dispenser, as shown and described.

DESCRIPTION

FIG. 1 is a top perspective view of a plastic film dispenser, showing my new design;

FIG. 2 is an exploded top perspective view thereof;

FIG. 3 is bottom perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof; and,

FIG. 10 is an enlarged view of portion 10 shown in FIG. 1. The broken lines are shown for the purpose of illustrating parts of the plastic film dispenser and form no part of the claimed design.

The dot-dash broken lines shown in FIGS. 1 and 10 represent the designation of an enlargement view and form no part thereof.

1 Claim, 10 Drawing Sheets
